UNITED STATES PATENT OFFICE.

CHESTER F. JOHNSON, OF DETROIT, MICHIGAN.

FUEL-VAPORIZING DEVICE.

1,117,392.

Specification of Letters Patent. Patented Nov. 17, 1914.

Application filed July 3, 1914. Serial No. 848,711.

To all whom it may concern:

Be it known that I, CHESTER F. JOHNSON, a citizen of the United States, and a resident of Detroit, in the county of Wayne and State of Michigan, have invented a new and Improved Fuel-Vaporizing Device, of which the following is a specification.

This invention relates to a device for vaporizing fuel for internal combustion engines.

After fuel is vaporized by carburetors or fuel feeders in the usual manner, it is found that many of the globules condense on the inner surface of the fuel passage thus impairing the efficiency of the engine. This action is accentuated on a cold day, and is also particularly noticeable during the starting of the engine.

The object of the present invention is to provide means whereby fuel which has failed to vaporize completely, or which, after having vaporized, has again condensed, may be carbureted before passing into the engine cylinder.

This invention consists in a novel heating means located in proximity to the passage between the mixing chamber of any desired form of fuel feeder and the intake of the engine.

It further consists in the details of construction shown and described, and particularly pointed out in the claims.

In the accompanying drawing, Figure 1 is a side elevation of a well-known form of engine provided with one embodiment of my invention. Fig. 2 is a vertical section through the upper end of the carburetor and the lower portion of the intake manifold shown in Fig. 1. Fig. 3 is a side elevation of a modification. Fig. 4 is a vertical section through the upper portion of Fig. 3. Fig. 5 is a perspective view of one end of the heating coil. Fig. 6 is a section of another modification.

Similar reference characters refer to like parts throughout the several views.

In the embodiment of my invention shown in Figs. 1 and 2, 1 indicates the drive-shaft, 2 the crank-case, 3 the cylinders, 4 the radiator, and 5 the exhaust manifold of a well known internal combustion engine. Connected to the engine in any desired manner is a carburetor 7 that may receive fuel through the pipe 8 from any convenient source.

The carburetor shown in Fig. 1 has a relatively long body portion 9 that extends from the mixing chamber to a point in proximity to the intake portion 10 of the intake manifold 11, and is there preferably provided with the flange 12. This flange is secured to the intake manifold in any desired manner, and may be spaced therefrom by the annular plate 14. This plate preferably has a laterally extending groove in one of its faces; and seated in the groove is the outer end 15 of a heating coil, the body of which extends into the fuel passage and is preferably given several circumferential turns 16. The inner end of the coil extends 70 into an annular chamber or well 18, formed by the ring 19 which is preferably L shaped in cross section. The coil is preferably coiled one or more times in this well as indicated at 21. While I prefer to form the 75 chamber or well 18 as shown in the drawing, it is obvious that it may be formed in various other ways; for example, the member 19 may be made integral with the body portion 9 of the fuel feeder.

It will be understood that such portions of the fuel as condense on the inner surface of the fuel conduit will drip downwardly over the various turns 16 of the heating coil, and if not vaporized before, will 85 finally be received in the well or chamber 18. Any fuel which collects in this chamber is then vaporized by the part 21 of the coil.

The member from which the coil is formed, as shown in Fig. 5, preferably comprises an inner resistance wire 23, an outer metallic tubular cover 24 to which the free end of the wire 23 may be soldered or otherwise secured at 25, and an insulating filling 26 separating the wire 23 and cover 24. The 95 wire 23 may connect to a binding post 27 with which the plate 14 is preferably provided, it being understood that this post is insulated from the plate 14 in any approved manner. If desired, a second binding post 100 29, positioned on the flange 12, or at any other point in electrical connection with the body of the carburetor, may be supplied.

Current entering at the binding post 27 passes through and heats the wire 23, which 105 is of relatively high resistance, then to the cover 24 and then to the body portion of the carburetor and to the binding post 29. The heat generated in the wire 23 warms the insulation 26 and cover 24, thus effectively 110

vaporizing the mist of fuel which has condensed on the inner wall of the part 9 as heretofore described.

In Figs. 3 and 4, my invention is shown applied to an engine in which the body of the carbureter is relatively shorter and the intake portion of the manifold correspondingly longer than in the embodiment previously described. In this instance the flanged end 12 of the body of the carbureter is spaced from the flange 31 on the intake portion 32 of the manifold by means of an annular plate 33 having an upwardly extending inner rim 34. This rim is spaced slightly from the inner wall of the manifold intake to form a well or chamber 35 in which fuel running down the inner surface of the intake may collect as before described. As in the previous case, the heating element may enter the fuel passage through a groove formed in the plate 33, and passes through the chamber 35 in one or more turns 36, after which it may be continued upwardly in the form of spiral turns 37 and 38 corresponding, respectively, to the posts 27 and 29, may be employed if desired. It will be understood that current may be supplied to the heating element from any appropriate source 40 by means of the wires 41 and 42 and switch bar 43, or one of the wires may be omitted, the circuit being grounded to the frame of the engine.

It is obvious that many changes may be made in the details of my construction without departing from the spirit of my invention. For example, the chambers 18 and 35 may be replaced, in certain instances, by a pad or ring of asbestos 44 or similar material, in which one or more turns 45 of the heating elements are embedded as shown in Fig. 6. I do not, therefore, desire to be limited otherwise than as indicated by the subjoined claims.

I claim:—

1. In combination, two members, one an intake for an internal combustion engine and the other a carbureter operatively connected thereto, said carbureter comprising a vaporizing chamber, means whereby an annular chamber is formed in the interior of one of the members at a point between the vaporizing chamber and the engine, said annular chamber serving to collect condensed or unvaporized fuel, and means for vaporizing the fuel which collects in the annular chamber.

2. In combination, two members, one an intake for an internal combustion engine and the other a carbureter operatively connected thereto, said carbureter comprising a vaporizing chamber, means whereby an annular chamber is formed in the interior of one of the members at a point between the vaporizing chamber and the engine, said an-

nular chamber serving to collect condensed or unvaporized fuel, and an electric heater, a portion of which extends into the annular chamber for vaporizing fuel collected therein.

3. In combination, two members, one an intake for an internal combustion engine and the other a carbureter operatively connected thereto, said carbureter comprising a vaporizing chamber, an annular member between the carbureter and the intake, said two first mentioned members and said annular member together having a passage that connects the vaporizing chamber with the cylinder of the engine, said annular member having a lateral opening, a conductor passing through the opening and terminating in an electric heater located in the passage for vaporizing condensed or unvaporized fuel which has passed through the vaporizing chamber of the carbureter.

4. A device for vaporizing fuel for an internal combustion engine comprising two metallic members, one an intake for the engine and the other a carbureter operatively connected thereto, said carbureter having a main vaporizing chamber, and said carbureter and said intake together including a passage that leads from the main vaporizing chamber to the engine, an electric heater located in said passage at a point between the main vaporizing chamber and the intake, said heater comprising an inner heating element, an insulating cover therefor, and a metallic protecting cover for the insulation, said heating element being electrically connected to the metallic cover and the cover being electrically connected to one of the two metallic members.

5. The combination with the fuel intake passage of an internal combustion engine, of a coiled heating element within the passage engaging with the inner wall thereof throughout its circumference so that drops of liquid fuel running down said wall may be heated.

6. The combination with the fuel intake passage of an internal combustion engine, of an annular receptacle and retainer within the passage in circumferential engagement with the inner wall thereof and projecting therefrom in such manner as to form a receiving chamber in which drops of liquid fuel running down said wall may be intercepted and retained, and electrical means for heating said liquid.

7. The combination with the fuel intake passage of an internal combustion engine, of a heating element coiled within the passage in engagement with the inner wall thereof so as to intercept and heat drops of liquid fuel running down said wall, said element consisting of a central wire of high resistance, a layer of insulation around the wire, and a metal protecting covering for

the insulation and connecting to one end of the wire to serve as a connector between the wire and the wall of the passage, and a circuit to a current source connecting to the other end of the wire.

8. In combination, two members, one an intake for an internal combustion engine and the other a carbureter operatively connected thereto, said carbureter comprising a vaporizing chamber, means whereby a circumferentially extending liquid receiver and retainer is formed in the interior of one of the members at a point between the vaporizing chamber and the engine, said liquid receiver and retainer contacting with the wall of the member in which it is located and serving to intercept condensed or unvaporized fuel running down said wall, and means for vaporizing the fuel which collects in the liquid receiver and retainer.

15 9. In combination, two members, one an intake for an internal combustion engine and the other a carbureter operatively connected thereto, said carbureter comprising a vaporizing chamber, means whereby an annular fluid receiver is formed in the interior of one of the members at a point between the vaporizing chamber and the engine, said annular receiver contacting with the inner surface of the member and serving to collect condensed or unvaporized fuel that runs down the said surface, and an electric heater for vaporizing the fuel collected in the fuel receiver.

20 10. In combination, means for forming a vaporizing chamber of a carbureter, means for forming a passageway from the vaporizing chamber to the cylinder of an internal combustion engine, means whereby a circumferentially extending liquid receiver and retainer is formed in the interior of the passageway, said liquid receiver and container contacting with the wall of the passageway and serving to intercept condensed or unvaporized fuel running down said wall, and means for vaporizing the fuel which collects in the liquid receiver and retainer.

25 11. In combination, means for forming a vaporizing chamber of a carbureter, means for forming a passageway from the vaporizing chamber to the cylinder of an internal combustion engine, means whereby a circumferentially extending liquid receiver and retainer is formed in the interior of the passageway, said liquid receiver and container contacting with the wall of the passageway and serving to intercept condensed or unvaporized fuel running down said wall, and means for vaporizing the fuel which collects in the liquid receiver and retainer.

30 12. The combination with the fuel intake passage of an internal combustion engine, of a coiled heating element within the passage engaging with the inner wall thereof throughout its circumference, the successive coils of the heating element being spaced apart from each other longitudinally of the passage so that drops of liquid fuel running down said wall may be progressively heated and vaporized.

35 In testimony whereof I have signed this specification in the presence of two subscribing witnesses.
